[57] **CLAIM**

The ornamental design for an air conditioner housing unit for the passenger compartment of a van, as shown and described.

DESCRIPTION

FIG. 1 is a left-front perspective view of the air conditioner housing unit with the rear top element in open condition, the manifold of the housing unit being shown in broken lines for illustrative purposes only and forming no part of the claimed design;

FIG. 2 is a right side elevational view thereof, the opposite side being a mirror image of that shown;

FIG. 3 is a top plan view thereof;

FIG. 4 is a front elevational view thereof;

FIG. 5 is a rear elevational view thereof; and,

FIG. 6 is a bottom plan view thereof.
